His Attorney.

UNITED STATES PATENT OFFICE.

ERNST F. W. ALEXANDERSON, OF SCHENECTADY, NEW YORK, ASSIGNOR TO GENERAL ELECTRIC COMPANY, A CORPORATION OF NEW YORK.

SYSTEM OF RADIO COMMUNICATION.

1,400,847.

Specification of Letters Patent.

Patented Dec. 20, 1921.

Application filed December 31, 1918. Serial No. 269,035.

To all whom it may concern:

Be it known that I, ERNST F. W. ALEXANDERSON, a citizen of the United States, residing at Schenectady, in the county of 5 Schenectady, State of New York, have invented certain new and useful Improvements in Systems of Radio Communication, of which the following is a specification.

My present application is a continuation 10 in part of my prior application, Serial No. 49,422, filed September 8, 1915.

My invention relates to systems of radio communication having a high frequency alternator as the source of radio energy.

15 While my invention in its complete aspect particularly relates to systems of radio communication, certain features of the invention are applicable generally to systems for the production of high frequency alternating 20 current of approximately constant frequency. Broadly, the object of my invention is to provide an improved continuous wave system of radio communication in which the source of radio energy is of approximately 25 constant frequency. More particularly the object of my invention is to provide a novel and improved speed regulating mechanism for a high frequency alternator employed as the source of high frequency energy in a 30 system of radio communication. In its more general aspect, my invention has for one of its objects the provision of improved means for regulating the speed of a high frequency alternator for generating high frequency alternating 35 current of substantially constant frequency. Other objects of my invention will be brought out in the course of the following description.

At the present time, there are two systems 40 of radio communication, the so-called damped wave system which is the system commonly used at the present day, and the continuous wave system, which now promises to become the predominating feature in 45 long distance systems of communication. Aside from the fact that the principle of wave motion is the same for both the damped and the continuous wave systems, the apparatus for sending, as well as for 50 receiving, is fundamentally different in the two systems. A continuous wave sending station consists of a source of high frequency alternating current energy which is delivered directly to the antenna. The simplest 55 form of the continuous wave system is an

alternating current generator of radio-frequency directly connected in series with the antenna. The receiver which is now largely used in continuous wave systems is the so-called heterodyne system. The heterodyne 60 receiving system depends upon the fact that the two waves of slightly different frequencies, when superimposed, create beats, with a beat-frequency equal to the difference between the two original frequencies. If, for 65 example, the radio-frequency is 100,000 cycles and an alternating current of 99,000 cycles is generated in the receiving station and superimposed upon the receiving circuit, a 70 beat-frequency of 1,000 cycles is created. While radio-frequencies are entirely inaudible, the beat-frequency of 1,000 cycles is one to which the human ear is most sensitive. The heterodyne receiver has an absolute selectivity for signals within the range of 75 about 5,000 cycles, which in practical commercial operation is the limit of audibility of the human ear. The beat-frequency, resulting from the interference of the incoming signal waves of radio-frequency and the 80 locally produced alternating current of slightly different frequency, is caused to produce a musical note by which the radio-signal is distinguished.

Since the signal in the heterodyne receiving system is distinguished by concentration of mind, on the part of the operator, on the sound of a certain musical note, and since the operator must distinguish this signal among a variety of other sounds, it is important that the sound of the receiving signal should be of practically constant pitch. The frequency of the sound wave for which the human ear is most sensitive is between 500 and 1,000 cycles per second, and in the heterodyne receiver it is desirable that the frequency of the effective sound wave should not vary more than about 25 cycles, per second. If the frequency of the radio current is 25,000 cycles, this would mean a variation of 100 0.1 per cent, and if the frequency of the radio current is 50,000 cycles, the permissible variation would be 0.05 per cent. Where the radio current is derived from a high frequency alternator, it will be evident that 105 a particularly uniform speed of the rotating member of the alternator is necessary. In fact, the requirements for constancy in speed regulation of regulators used with high frequency alternators in continuous 110

wave systems of radio communication with heterodyne receivers are more severe than in any other electrical apparatus or system with which I am acquainted.

5 My present invention has for one of its objects to maintain at a predetermined value the speed of a high frequency alternator driven by a prime-mover deriving its power from an electric circuit. The invention is 10 based upon the principle of sharp resonance in an auxiliary circuit acting, for example, upon the field of an electric motor driving the alternator, upon the field of an electric generator supplying energy to the motor or 15 upon the circuit which supplies current to the driving motor. In accordance with my invention the current in the resonant circuit is rectified, and the rectified current acts directly, or through some amplifying means, 20 upon the agency which is to be controlled.

The problem of providing any automatic mechanism intended for maintaining constancy of some quantity, like speed or voltage, is attended with considerable difficulties. The principal difficulty lies in controlling the inertia of the various functions that take part in the regulation, such as the inertia of the water in the pipe line of a turbine regulator, or the magnetic inertia in the 30 field of a dynamo electric machine. Unless special precautions are taken to control this inertia, the regulator does not work properly, or, as it is termed, is apt to hunt, and consequently a variety of methods and 35 means have been worked out depending upon the practical conditions surrounding each problem of regulation. As for instance may be mentioned shunt-flow in the water wheel regulator, and the floating contact and 40 anti-hunting contact in the Tirrill voltage regulator. In each of these cases, advantage is taken of the fact that the changes in load are usually slow, relative to the action of the parts of the regulator, and it is permissible 45 to slow down the action of the regulator so as to allow it to gradually adjust itself to the new condition, thereby avoiding over-regulation and consequent hunting.

In providing a speed regulator for a radio-frequency alternator, the problem is 50 made additionally difficult, not only on account of the very exacting requirement of constancy, but on account of the fact that the whole power-flow is changed at a very 55 rapid rate during the sending of telegraph signals. Any method of avoiding hunting by slowing down the action of the regulator would not, therefore, be acceptable.

My present invention consists in providing 60 a regulator mechanism which has the required high accuracy and quickness of action by introducing devices which so greatly magnify the indications of change of speed that these devices will in effect anticipate 65 and reverse the action of the regulator parts

before the inertia of the regulating function has carried it beyond the permissible limit. More specifically, my present invention comprises the use of a highly tuned electric circuit energized by a current derived from the 70 high frequency alternator, whose speed is to be regulated, together with a rectifier associated with the tuned circuit and delivering rectified current to a relay for controlling the rest of the regulating mechanism. 75 In addition, I preferably employ means for further amplifying the variations in energy, which act upon the movable part of the regulator relay, after such variations in energy have been transferred from the tuned or oscillating circuit to the rectified circuit and thence to the winding of the relay. The means for amplifying the variations of energy acting upon the regulator relay preferably operate upon the differential principle where a variable force is opposed by a 80 constant force, so that the resulting force has a greater percentage of variation than the original variable force. The differential arrangements that may expediently be used 85 include the opposition of a constant electro-motive force against the rectified electromotive force,—the opposition of the tension of a spring against the force of the magnet in the regulator relay,—the opposition of a 90 permanent magnetic field in the relay against the field superimposed by the magnetism of the relay, or the use of the differential action between the radio frequency and a slightly different frequency in a manner analogous to the heterodyne receiver. All of these methods for amplifying the variations of energy acting upon the relay 95 may be used in combination, or any one may be used alone. Those skilled in the art will 100 recognize that many other equivalent means and their combinations may also be devised for accomplishing the same purpose.

The system which I have chosen to illustrate the principle of my invention comprises a high frequency alternator driven by three-phase electric motor supplied with electric energy from a distribution system. The regulator relay operated in the manner hereinbefore described is employed to control the flow of power delivered to the shaft of the alternator, and the character of the controlling device used for this purpose will of course depend upon the source of power which is employed to drive the alternator. 110 Where an alternating current electric motor is employed as in the system illustrated, the flow of power to the alternator shaft may be controlled by regulating the current supply 115 to the motor.

The novel features which I believe to be characteristic of my invention are set forth with particularity in the appended claims. The invention itself, however, as to its organization and method of operation, to 120 125 130

gether with further objects and advantages thereof, will best be understood by reference to the following description taken in connection with the accompanying drawing in which I have illustrated diagrammatically one way in which my invention may be carried into effect.

The system illustrated in the accompanying drawing comprises the usual antenna 1 with the tuning inductance 2. The antenna is connected to the armature winding of a radio frequency alternator 3 through a radio transformer having a secondary winding 4. The armature of the alternator 3 has a plurality of coils 5 independently connected to a plurality of primary coils 6 supplying current to the secondary 4 of the transformer. The secondary winding 4 of the transformer is in series with the tuning coil 2 and the antenna 1 and has one terminal connected to ground in the well known manner. The radio frequency alternator, which I have diagrammatically represented in the drawing, is of the inductor type described in my U. S. Letters Patent No. 1,008,577, November 14, 1911, No. 1,110,029, September 8, 1914, and No. 1,110,030, September 8, 1914. The alternator has a stationary laminated iron armature member carrying the coils 5 and has a rotatably mounted rotor or inductor member in the shape of a disk designed for maximum strength and having a plurality of slots for producing magnetic poles therebetween. The inductor rotor of the alternator is represented in the drawing at 7 and is mounted on a rotatable shaft 8. A three-phase alternating current motor 9 is also coupled to the shaft 8 and operates to drive the inductor 7 of the alternator. The motor 9 receives power from the supply conductors 10. The current supplied to the motor is controlled by a variable impedance or saturation regulator which comprises magnetic cores 11 with windings 12 thereon, which carry the current supply to the motor, and with additional windings 13 which carry the saturating current of the cores 11, which is used for controlling the current supply to the motor. The operation of this regulator will be described more in detail later.

The flow of power from the high frequency alternator to the antenna, and hence the energy radiated from the antenna, is controlled by a magnetic controller or amplifier. This magnetic amplifier is of the type described in the Letters Patent of the United States of James C. Armor, No. 1,219,215, while the particular form of the controller which may be used, may be of the type described at length in my copending applications for Letters Patent of the United States, Serial No. 63,438, filed November 26, 1915, and Serial No. 227,946, filed April 11, 1918.

In the circuit connection here illustrated

the magnetic amplifier comprises two reactive windings 14, wound upon separate magnetic cores so that their magnetic actions are relatively opposed. The two reactive windings 14 are surrounded by a controlling winding 15 adapted to be supplied with direct current from any suitable source such as a battery 16. The reactive windings 14 are connected in shunt to the secondary winding of the transformer 4. A telegraph key 17 controls the flow of current in the winding 15. When the telegraph key 17 is in the position shown in the drawings the controlling winding 15 is energized and the impedance of the reactive windings 14 is a minimum so that the secondary winding 4 is substantially short-circuited and little or no energy is radiated from the antenna 1. When it is desired to send a signal, telegraph key 17 is depressed, thereby opening the circuit of the controlling winding 15, whereupon the impedance of the reactive windings 14 is raised to its maximum value and energy is radiated from the antenna. Power is thus taken on and off the alternator by operation of the telegraph key.

The speed regulator for the alternator should act in such a way that the power of the motor 9 is changed with the telegraph signals so that the torque of the motor is varied an amount corresponding to the load on the alternator before an appreciable change in speed of the generating unit has taken place.

The current supplied to the motor 9 may be varied by varying the magnetic saturation of the cores 11, and hence varying the impedance of the windings 12, which are in series with the source of supply. The current supply for saturating the cores 11 is obtained from a direct current generator 18. The approximate adjustment of the torque of the motor 9 may be obtained by means of a resistance 19 which is included in the circuit which supplies current from the generator 18 to the saturation coils 13. This resistance is controlled by the manipulation of the telegraph key. When the telegraph key is depressed to send a signal the resistance 19 is short-circuited by the engagement of the key with the fixed contact 20. The current in the saturation current coils 14 is thereby increased and the current supplied to the motor and hence the torque of the motor, is increased to approximately correspond to the change in the load on the alternator.

The tuned circuit of the automatic speed regulating mechanism is fed from one of the independent armature circuits of the alternator, and the voltage supplied thereto is thereby rendered independent of the load on the machine. This circuit includes an adjustable inductance 21 for tuning purposes, a condenser 22 and the primary 23 of a trans-

former. The secondary 24 of this transformer is included in the rectifier circuit which also includes the rectifier 25 and the winding 26 of the relay 27. In the present 5 case a mercury vapor rectifier is shown but this is not essential as other forms of rectifier may be used if desired. The regulator can be adjusted for different speeds and corresponding frequencies by changing the inductance of the coil 21 in the tuned circuit. 10 This change can obviously also be made by changing the capacity of the circuit or by changing both capacity and inductance. Variations in the adjustment may also be accomplished 15 if desired by varying the coupling between the primary 23 and the secondary 24 of the transformer which supplies energy to the rectifier circuit.

When a mercury vapor rectifier is used in 20 a regulating mechanism embodying my invention, the counterelectromotive force of a few volts of the rectifier provides a differential means for emphasizing or accentuating the variations in the rectified current 25 hereinbefore mentioned. The voltage necessary for maintaining the rectifier continuously in an operating condition is supplied by a direct current generator 28 which is connected to the rectifier in the well known 30 manner.

With the arrangement which I have shown the rectified voltage supplied from the alternator must exceed the counter electromotive force of the rectifier before any current will flow in the rectified circuit. The current flowing in the winding 26 is thus determined by the difference between the rectified voltage and the counter electromotive force due to the rectifier and a change in the rectified 40 voltage thus produces a greater percentage change in the relay current than would be the case if the differential action of a counter electromotive force were not employed. In this way a particular change in the rectified 45 voltage becomes more effective, or in other words, is accentuated or emphasized. It will of course be apparent that any other rectifier which has a counter electromotive force will produce the same effect.

The relay 27 has a movable element or armature 29, which opens and closes a contact 30. When the armature 29 is in the position indicated, the winding 31 of a second relay 32 is short-circuited. When, however, 55 the armature 29 operates to open the contact 30 this short-circuit is removed and current from the direct current generator 28 is supplied to the winding 31 to operate the relay 32. The opening and closing of 60 contact 33 of the relay 32 serves to open and close the circuit of the field winding 34 of the generator 18, which supplies current to the saturation coils 13. Thus whenever the magnetizing action of the relay 27, due to 65 the current flowing in its winding 26 is suf-

ficiently great to attract the armature 29 the field winding 34 of the generator 18 is opened and the saturation current supplied to the coils 13 is interrupted.

The relay 27 is provided in addition to 70 the winding 26 with a second winding 35 which is supplied with current from the generator 18. This winding is so arranged as to assist the winding 26 in attracting the armature in opposition to the pull of spring 75 36. When the armature 29 is attracted so as to open contact 30 and the field 34 of generator 18 is thus opened, the current supplied to winding 35 is reduced and the armature 29 is at once pulled up by spring 80 36 to reestablish the contact 30. As a result of this action the contacts 30 and 33 are caused to vibrate at a high rate of speed, maintaining a pulsating voltage on the generator 18. 85

The resonant circuit which supplies current to the rectifier 25 is preferably adjusted for a frequency slightly higher than that at which the alternator is intended to operate. As a result a slight increase in the 90 speed of the alternator will produce a large increase in the current in the rectifier circuit supplied to the winding 26 of relay 27. This will cause the relay 27 to operate somewhat sooner than it would with the normal 95 current in the rectifier circuit, and consequently the field circuit of generator 18 will be opened sooner and remain open for a longer interval than under normal conditions. As a result less current will be supplied 100 to the saturation coils 13 and the current supplied to the motor 9 will decrease, slowing down the alternator.

The operation of the regulating system will be improved by the use of a condenser 105 37 in shunt to the secondary 24 of the transformer by which current is supplied to the rectifier. Since the current in the rectifier circuit is a high frequency pulsating current a condenser 38 is preferably inserted in 110 shunt to the winding 26 in order to smooth out the pulsations in the current supplied to that winding. When the coils 12 of the saturation regulator are connected, as shown, they form a low resistance secondary 115 for the saturation coils 13 in order to permit the current in the saturation coils 13 to quickly build up to its maximum value, it is therefore desirable to provide resistances 39 in series with the coils 12. The 120 rheostat 40 is provided for adjusting the saturation current supplied to the coils 13 when the key 17 is depressed. The rheostat 41 admits the adjustment of the current supplied to the winding 35 and the rheostat 125 42 is provided for adjusting the current in the field 34 of generator 18.

It will be evident from the foregoing description that the speed regulating mechanism involved in my invention is extremely 130

sensitive. The rectified or unidirectional current in the rectifier circuit varies at a greater rate than the current in the tuned circuit which supplies current to the rectifier circuit. The regulating relay is also of a peculiarly sensitive type so that the force which actuates the movable armature of the relay varies at a greater rate than the square of the current in the resonant circuit by reason of the differential action between the spring 36 and the forces acting in opposition thereto. The regulator relay will thus reverse the action of the means controlling the power flow to the alternator shaft before

10 son of the differential action between the spring 36 and the forces acting in opposition thereto. The regulator relay will thus reverse the action of the means controlling the power flow to the alternator shaft before

15 sufficient inertia has been given to the controlling function to make the power flow over travel more than the amount corresponding to a change in radio frequency that would give a low note in a telephone.

20 The flow of energy to the alternator shaft is therefore so controlled that the difference between the maximum and minimum frequencies of the alternator corresponds to a frequency not higher than one which would produce a low note in a telephone.

25 While I have described a single embodiment of my invention, it will be apparent to one skilled in the art that my invention is not limited to the precise arrangement shown but that many modifications may be made in the circuit arrangements and apparatus used without departing from the scope of my invention as set forth in the appended claims.

30 35 What I claim as new and desire to secure by Letters Patent of the United States, is:—

1. A system for the production of high frequency alternating current of substantially constant frequency comprising in combination a high frequency alternator, an auxiliary electric circuit electrically associated with said alternator and adapted to receive a current of the frequency generated by the alternator, a current rectifying electric circuit electrically associated with said auxiliary electric circuit, means whereby the current-flow in said rectifying circuit has a greater rate of variation than the current-flow in said auxiliary circuit, and means responsive to variations in the current-flow in said rectifying circuit for varying the speed of said alternator.

40 45 50 55 60 65 70 75 80 85 90 95 100 105 110 115 120 125 130

2. A system for the production of high frequency alternating current of substantially constant frequency comprising in combination a high frequency alternator, an auxiliary electric circuit sensitive to variations in frequency electrically associated with said alternator, electric current rectifying means associated with said auxiliary circuit, and means responsive to the rectified current resulting from the action of said last mentioned means for controlling the speed of said alternator.

3. A system for the production of high

frequency alternating current of substantially constant frequency comprising in combination a high frequency alternator having a plurality of independent armature circuits, a source of power for driving said alternator, means for deriving from one of the armature circuits of said alternator a unidirectional electric current varying as a function of the frequency of the current generated by the alternator, and means responsive to changes in the value of said unidirectional current for varying the application of power from said source to said alternator.

4. A system for the production of high frequency alternating current of substantially constant frequency comprising in combination a high frequency alternator, a source of power for driving said alternator, an electric circuit associated with said alternator and adapted to receive a current of the frequency generated by the alternator, means for tuning said circuit for a frequency slightly different than the frequency of the alternator current, means for producing a unidirectional electric current corresponding to the alternating current flowing in said electric circuit, and means responsive to changes in the value of said unidirectional current for varying the application of power from said source to said alternator.

5. A system for the production of high frequency alternating current of substantially constant frequency comprising in combination a high frequency alternator having a plurality of independent armature circuits, a source of power for driving said alternator, a tuned electric circuit associated with said alternator and adapted to receive from one of said armature circuits a current of the frequency generated by the alternator, means for producing a unidirectional electric current corresponding to the current flowing in said tuned circuit, and electromagnetic means responsive to changes in the value of said unidirectional current for varying the application of power from said source to said alternator.

6. A system for the production of high frequency alternating current of substantially constant frequency comprising in combination a high frequency alternator, a source of power for driving said alternator, a tuned electric circuit associated with said alternator and adapted to receive a current of the frequency generated by the alternator, means for producing a unidirectional electric current corresponding to the current flowing in said tuned circuit, means for emphasizing the variations in said unidirectional current, and means responsive to the emphasized variations in said unidirectional current for varying the application of power from said source to said alternator.

7. A system for the production of high frequency alternating current of substantially constant frequency comprising in combination a high frequency alternator, a prime-mover for driving said alternator, a tuned electric circuit associated with said alternator and adapted to receive a current of the frequency generated by the alternator, a second electric circuit electrically associated with said tuned circuit, an electric current rectifying device in said second circuit, a relay responsive to changes in the current flowing in said second electric circuit, and means controlled by said relay for varying the speed of said prime-mover. 70
8. A system of electrical distribution comprising in combination a high frequency alternator, an auxiliary electric circuit sensitive to variations in frequency electrically associated with said alternator, a current rectifying electric circuit electrically associated with said auxiliary circuit, and having an approximately constant counter-electromotive force which opposes the flow of current in said rectifying circuit, and a relay included in said rectifying circuit and adapted to vary the speed of said alternator. 75
9. A system of electrical distribution comprising in combination a high frequency alternator, an auxiliary electric circuit sensitive to variations in frequency electrically associated with said alternator, electric current rectifying means associated with said auxiliary circuit, a relay having a movable armature responsive to the rectified current resulting from the action of said last mentioned means, means whereby the force actuating the movable armature of said relay varies at a greater rate than the square of the current in the auxiliary circuit sensitive to frequency variations, and means controlled by the movable armature of said relay for varying the speed of said alternator. 80
10. A system of electrical distribution comprising in combination a high frequency alternator, means for supplying energy to the shaft of said alternator, an auxiliary electric circuit sensitive to variations in frequency electrically associated with said alternator, electric current rectifying means associated with said auxiliary circuit, a relay responsive to the rectified current resulting from the action of said last mentioned means, means controlled by said relay for varying the speed of said alternator, and means for emphasizing the effect of said rectified current. 85
11. A system of electrical distribution comprising in combination a high frequency alternator, an auxiliary electric circuit sensitive to variations in frequency electrically associated with said alternator, electric current rectifying means associated with said auxiliary circuit, a relay responsive to the rectified current resulting from the action of said last mentioned means, means controlled by said relay for varying the speed of said alternator, and means for emphasizing the effect of said rectified current. 90
12. A speed regulating system comprising an alternating current generator, a source of power for driving said generator, means for deriving from said generator a unidirectional electric current which varies as a function of the frequency of the current generated thereby, and means responsive to changes in the value of said unidirectional current for varying the application of power from said source to said generator. 95
13. A speed regulating system comprising an alternating current generator, a source of power for driving said generator, a tuned electric circuit associated with said generator and adapted to receive a current of the frequency generated, means for producing a unidirectional electric current corresponding to the current flowing in said tuned circuit, and electromagnetic means responsive to changes in the value of said unidirectional current for varying the application of power from said source to said generator. 100
14. A system for the production of high frequency alternating current of substantially constant frequency comprising in combination a high frequency alternator, an electric motor for driving said alternator, a tuned electric circuit associated with said alternator and adapted to receive a current of the frequency generated by the alternator, a second electric circuit electrically associated with said tuned circuit, an electric current rectifying device in said second circuit, a relay responsive to changes in the current flowing in said second electric circuit, and means controlled by said relay for varying the current supplied to said motor. 105
15. A system for the production of high frequency alternating current of substantially constant frequency comprising in combination a high frequency alternator, an alternating current motor for driving said alternator, a tuned electric circuit associated with said alternator and adapted to receive a current of the frequency generated by the alternator, a second electric circuit electrically associated with said tuned circuit, a relay responsive to changes in the current flowing in said second electric circuit, a supply circuit for supplying current to said motor, a variable impedance in said supply circuit, and means controlled by said relay for varying the value of said impedance. 110
16. A system for the production of high frequency alternating current of substantially constant frequency comprising in combination a high frequency alternator having a plurality of independent armature coils, a prime-mover for driving said alternator, a tuned electric circuit associated with one of 115
17. A system for the production of high frequency alternating current of substantially constant frequency comprising in combination a high frequency alternator having a plurality of independent armature coils, a prime-mover for driving said alternator, a tuned electric circuit associated with one of 120
18. A system for the production of high frequency alternating current of substantially constant frequency comprising in combination a high frequency alternator having a plurality of independent armature coils, a prime-mover for driving said alternator, a tuned electric circuit associated with one of 125
19. A system for the production of high frequency alternating current of substantially constant frequency comprising in combination a high frequency alternator having a plurality of independent armature coils, a prime-mover for driving said alternator, a tuned electric circuit associated with one of 130

- 5 said armature coils, means for producing a unidirectional current corresponding to the current flowing in said tuned circuit, an electromagnetic means responsive to changes in the 10 value of said unidirectional current for varying the application of power from said prime-mover to said alternator.
17. A speed regulating system comprising an alternating current generator, an electric 10 motor for driving said generator, a source of current for controlling the speed of said motor, means for deriving from said generator a unidirectional electric current which varies as a function of the frequency of the 15 current generated thereby, and means responsive to changes in the value of said unidirectional current for controlling the voltage of said source of current and thereby controlling the speed of said motor.
- 20 18. A speed regulating system comprising an alternating current generator, an electric motor for driving said generator, a source of current for controlling the speed of said 25 motor, means for deriving from said generator a unidirectional electric current which varies as a function of the frequency of the current generated thereby, and means responsive to changes in the value of said unidirectional current and to the voltage of said 30 current source for varying the current supplied from said source, and thereby controlling the speed of said motor.
19. A speed regulating system comprising an alternating current generator, an electric 35 motor for driving said generator, a source of current for controlling the speed of said motor, means for deriving from said generator a unidirectional electric current which varies as a function of the frequency
- of the current generated thereby, an electromagnetic means responsive to changes in the value of said unidirectional current and of the voltage of said source of current for varying the current supplied by said source, and thereby controlling the speed of said 40 motor.
20. A system for the production of high frequency alternating current of substantially constant frequency comprising in combination a high frequency alternator, an 45 electric motor for driving said alternator, a source of current for controlling the speed of said motor, means for deriving from said alternator a unidirectional current which varies as a function of the frequency of the 50 current generated thereby, and a relay responsive to changes in the value of said unidirectional current and the voltage of said source of current, for controlling the current supplied from said source, and thereby controlling the speed of said motor.
21. A system for the production of high frequency alternating current of substantially constant frequency comprising in combination a high frequency alternator having 55 a plurality of independent armature circuits, an auxiliary electric circuit sensitive to variations in frequency electrically associated with one of the armature circuits of said alternator, electric current rectifying means 60 associated with said auxiliary circuit, and means responsive to the rectified current resulting from the action of said last mentioned means for controlling the speed of said alternator.

In witness whereof, I have hereunto set my hand this 30th day of December, 1918.

ERNST F. W. ALEXANDERSON.
